DESIGN FOR A WATCHCASE

Ben Ogush, New York, N. Y., assignor to Katz & Ogush, Inc., New York, N. Y., a corporation of New York

Application February 18, 1938, Serial No. 75,245

Term of patent 7 years

To all whom it may concern:

Be it known that I, Ben Ogush, a citizen of the United States and a resident of the city, county, and State of New York, have invented a new, original, and ornamental Design for Watchcases, of which the following is a specification, reference being had to the accompanying drawing forming a part thereof, in which

Fig. 1 is a face view of a watchcase showing my new design, and Fig. 2 is a side view of the same.

I claim:

The ornamental design for a watchcase, as shown.

BEN OGUSH.
